UNITED STATES PATENT OFFICE.

JAMES ALLEN SWAINBANK, OF WELLAND, ONTARIO, CANADA.

TRAILING WEFT-END-CLEARER DEVICE FOR LOOMS.

Application filed July 19, 1923. Serial No. 652,535.

To all whom it may concern:

Be it known that I, JAMES ALLEN SWAINBANK, a subject of Great Britain, residing at Welland, in the Province of Ontario, Dominion of Canada, have invented a certain new and useful Improvement in Trailing Weft-End-Clearer Devices for Looms, of which the following is a specification, reference being had therein to the accompanying drawings.

The invention is applicable to automatic looms employing filling-feelers and of the type wherein the working supply of weft or filling is replenished by automatically inserting a fresh filling-carrier into the working shuttle and simultaneously ejecting from the shuttle the old filling-carrier from which the supply of weft or filling has been substantially exhausted. When the old filling-carrier is driven out through the bottom of the shuttle in the replenishing operation, with more or less residue of wound filling still remaining upon the filling-carrier, as is the case in looms in which the replenishing instrumentalities are controlled by filling-feelers, the yarn from this carrier still remains engaged in the eye of the shuttle, so that frequently the old weft-end is held by the shuttle-eye and carried into the warp-shed, to produce a fault in the fabric known as a "double pick," or else fouls the new weft-end and causes breakage thereof. This failure of the old weft-end to clear itself from the shuttle-eye is regarded by users of bobbin-changing automatic looms as one of the greatest drawbacks of the looms aforesaid, inasmuch as when the shuttle-eye becomes clogged with lint in the least, or the shuttle becomes worn on the side thereof so that the groove thereon is shallow, or even when everything is ideal, there is always liability of the old weft-end being dragged into the shed.

Various devices have been proposed for the purpose of preventing the old or trailing weft-end from being carried into the shed as aforesaid, but none of such devices, as far as I am aware, is in general use in practice at the present time.

The invention consists in a weft-end clearer device of novel and improved construction having as a characteristic feature a yarn-engaging member which occupies a stationary forward retracted position while the lay is rearward, and is given by the lay in the latter's advancing movement a

position at the rear of the path in which the ejected filling-carrier falls from the shuttle, so that as the lay moves rearward and the said member moves forward an old or trailing weft-end extending upward from the ejected bobbin in the catcher-box to the shuttle-eye will be engaged by such member, thereby providing for clearing the weft-end from the shuttle-eye, and safeguarding against such end being carried into the shed by the shuttle.

A second feature of the invention is a coacting member with which the member first mentioned cooperates in its retracted position to clamp the weft-end and thereby more effectually guard against such end being carried into the shed.

The drawings show an illustrative embodiment of my invention combined with parts of a bobbin-changing loom. The general construction of the ordinary types of automatic looms is so well-known and familiar to those skilled in the art that only a fragmentary showing and a very general description of the parts associated with the operation of my device is deemed necessary.

In the drawings,—

Fig. 1 is a partly sectional view of portions of a bobbin-changing loom, showing an embodiment of my invention applied thereto.

Fig. 2 is a somewhat similar view, on an enlarged scale, of some of the parts of Fig. 1, with the addition of a catcher-box for expelled bobbins, the section being on line 2, 2, in Fig. 3.

Fig. 3 is a front elevation of certain of the parts of Fig. 2, on the same enlarged scale.

Fig. 4 is a partly sectional plan view, the section being on line 4, 4, in Fig. 3.

Fig. 5 is an isometric view of the trailing-end clearer of the preceding views, shown separately.

Referring to the drawings,—

The lay-beam is shown at 1, and 2 (Figs. 1 and 2) is the breast-beam, upon which is mounted the magazine 3 holding the fresh bobbins or filling-carriers 4, 4, in readiness to be driven down, each in turn, into the shuttle 5 within the shuttle-box 6 on the lay-beam 1, when the depletion-indicating devices of the loom detect the predetermined extent of exhaustion of the working supply of filling on the bobbin in the shuttle. In usual practice, the change of bob-

bins is effected in well-known manner when the lay is at front center, that is, at the end of its forward travel, through the downward blow of the transerrer 7 driving 5 down the fresh bobbin 4 which is immediately under it into the shuttle 5, the fresh bobbin in turn expelling the substantially empty bobbin from the shuttle downwardly through the opening in the lay and upon 10 the bobbin-chute 8 provided on the lay-beam directly under the shuttle-box 6. In usual practice the transerrer 7 is mounted pivotally on a stud 10 projecting outwardly from the stand 9 on the breast-beam which supports 15 the magazine 3; it is actuated to occasion its downward stroke through the engagement of bunter 71 carried by the lay with the dog or latch 72 hung to the downwardly extending arm 73 of the transerrer, the 20 said engagement of the dog or latch by the bunter being controlled by the depletion indicating mechanism referred to above.

Referring now to the novel means which I propose for withdrawing the trailing weft-end α which extends upwardly from the just-expelled bobbin occupying the bobbin catcher-box γ , as in Fig. 2, to and through the eye of the shuttle 5, a downwardly extending arm 11 is mounted upon 30 the outer end-portion of the stud 10, it being held in fixed position on said stud by means of a clamping screw 101. The arm may be swung around the stud 10 into the desired position forward or rearward, and be fastened in such position by means of the clamping screw. This adjustment enables the position of the device which engages with the trailing weft-end to be varied forward or rearward as may be required to conform to the stroke of the lay and to secure the desired operation of such device. To the lower end of arm 11 is secured a rearwardly extending arm 12, an upturned flange 120 at the forward end of 40 said arm 12, having a vertical slot 121 therein, being provided to receive the clamping bolt 122 which combines the two arms, the said slot and bolt providing adjustment means whereby the angle between the two arms and the elevation of arm 12 may be varied as required. A horizontal slot 110, Fig. 2, in the lower end of arm 11 provides for a certain amount of adjustment of arm 12 forwardly and rearwardly relative to 50 arm 11. At the rearward end of arm 12 is pivoted an arm 13 forming the clearer proper. The pivot pin combining the arm 13 with supporting arm 12 is a stud 14 which is flattened or otherwise prevented 55 from axial rotation at the point where it passes through arm 12. A spring 15 encircling the extension of stud 14 below arm 12 has one of its ends brought upward to bear against the tail 130 of arm 13, while 60 the other end of the spring 15 is anchored

to the collar 16 which is fixed non-rotatably upon the stud 14 in some suitable manner, as by providing the collar with a plurality of threaded holes through which may be entered a clamping screw 161 to engage a 70 hole formed in the stud 14. In adjusting the parts for proper operation, the collar 16 is rotated about the axis of stud 14 until a sufficient degree of tension has been given to the spring 15 to hold arm 13 normally 75 pressed firmly against a stop 123 formed on the outward edge of arm 12 adjacent the said upturned flange 120 on such arm; the collar is then secured to the stud 14 by the proper engagement of clamping screw 161. 80 A nut 142 and nut-locking pin 143 retain the arm 13 in place upon said stud 14.

The trailing weft-end clearer device 13 is positioned so that as the lay advances the said device will enter the narrow horizontal space shown in Fig. 3 between the underside of lay-beam 1 and the top edge of the outer portion of chute 8, and so that a dog or striker 17 upon the bobbin-chute 8 will strike the tail 130 of such device. The stud 14 forming the pivot on which the arm 13 swings is offset inwardly of the loom with respect to the dog or striker 17, so that the advance of the lay and pressure of dog or striker 17 will cause the main portion of 95 arm 13 to swing rearwardly from its normally retracted forward position shown by full lines in Figs. 1 and 5, and by dotted lines in Fig. 4, into the position shown in full lines in Figs. 2, 3, and 4, and dotted 100 lines in Fig. 5, rearward of the path in which the expelled bobbin falls on its way to the catcher-box γ , Fig. 2. As a result, the trailing weft-end α extends down from the shuttle-eye in front of the thus-positioned clearer device. As the lay recedes, the spring 15 acts to restore arm 13 to its normal retracted position overlying arm 12. The forward sweep of said arm 13 engages any trailing weft-end which extends upward from the expelled old bobbin in the catcher-box, through the opening in the lay and through the eye of the shuttle; it carries such trailing weft-end with it as it closes upon arm 12, and wedges it firmly 115 between itself and the arm 12, so that if the weft-end is not already drawn clear of the shuttle and its eye, it speedily becomes so as the lay recedes. The clearing arm 13 is provided with a slight nose 131, Figs. 4 and 5, at its free end to keep the weft-end from slipping off the arm at such point as the arm swings forward.

The spring 15 is compressed axially to a slight degree as the collar 16 is applied, so that its axial expansion keeps the clamping arm 13 and arm 12 pressed closely together to insure the gripping of the yarn between them. The hole through arm 12 for the flat-sided stud 14 is in the form of a slot, to 125

permit slight divergence of the coacting arms 12 and 13 from the primary stage of horizontal parallelism, to take care of an accumulation of weft-ends between them; the stud 14 can tip slightly in the said slot for this purpose, or rise against the resistance of spring 15.

In the full-line position occupied by the clearer device 13 in Fig. 4, it serves as a means of preventing an ejected bobbin from getting into the slot 31 in which the picker-stick works inward and outward, and thereby safeguards against breakage of bobbins, and against banging-off of the loom as a result of a bobbin getting into the slot.

If the filling-feeler devices are removed or rendered inoperative and the action of the bobbin-changing mechanism is controlled by the weft-fork mechanism instead, the arm 13 may be utilized solely as a means of preventing bobbin smashes, by adjusting collar 16 to relax spring 15 so that the latter has no tendency to swing the arm 13, and then tightening collar 16 up hard against spring 15, to hold the clearing arm 13 continuously in its rearward position shown in full lines in Fig. 4.

What I claim as my invention is,—

1. Weft-clearer devices comprising a stationary support, a weft-clearer movably mounted on said support, occupying a retracted forward position while the lay is rearward, and actuated by the advancing lay into a position rearward of the path in which the ejected filling-carrier falls from the shuttle.

2. The combination with a stationary support of a weft-clearer movably mounted in connection therewith, occupying a retracted forward position while the lay is rearward and actuated by the advancing lay into a position rearward of the path in which the ejected filling-carrier falls from the shuttle, and means actuating said weft-clearer to engage the trailing weft-end from said filling-carrier as the lay recedes.

3. A weft-clearer for looms comprising a stationary supporting member, a swinging member pivoted thereto adapted to be swung rearwardly by the action of the advancing lay-beam into a position rearward of the path of the descending ejected filling-carrier, and means causing said swinging member to swing forwardly as the lay recedes.

4. A weft-clearer for looms comprising a stationary supporting member, a lever pivoted upon said member having an arm adapted to be struck by the advancing lay-beam to swing the weft-end engaging arm thereof to the rear of the path in which the ejected filling-carrier falls, and means for swinging the lever to carry the said weft-end engaging arm forwardly as the lay recedes.

5. A weft-clearer for looms comprising

a rearwardly extending stationary supporting member, a swinging arm pivoted to the said supporting member for horizontal swinging movement and having a tail adapted to be struck by the advancing lay-beam to swing the arm rearwardly into position for engagement with a trailing weft-end, and a spring serving to swing the swinging arm forwardly as the lay recedes, to engage the trailing weft-end from said ejected filling-carrier, and also serving to press the swinging arm against the supporting member to clamp said weft-end.

6. A weft-clearer for looms comprising, in combination with the transerrer stud, a supporting arm mounted on the transerrer stud, a rearwardly extending arm on said supporting arm adjustably combined therewith, a swinging arm pivoted on said rearwardly extending arm and adapted to be swung rearwardly through contact with the advancing lay into position for engagement with a trailing weft-end, and a spring at the pivotal point to swing the swinging arm forward as the lay recedes so as to engage and carry forward the trailing weft-end, and also to press the swinging arm flatwise against the rearwardly extending arm so as to clamp the said weft-end between the swinging arm and the rearwardly extending arm.

7. A weft-end clearer for looms comprising a stationary support, an arm pivotally combined with said support and adapted to be swung in one direction by contact with the lay-beam into position for engagement with a trailing weft-end and a spring operating to swing said arm reversely and to cause it to overlap the other arm so as to clamp the said weft-end between the adjoining surfaces of said arms.

8. A weft-end clearer for looms according to claim 7 in which one of the pivotally combined members has an oversized hole for the pivot-pin, to admit of divergence of the two members from a parallel relation, to provide for an accumulation of weft-ends between the adjoining surfaces.

9. Trailing weft-end clearer devices comprising a stationary support, a weft-clearer movably mounted on said support, occupying a retracted forward position while the lay is rearward, and actuated by the advancing lay to move its engaging portion into a rearward position adapting such portion to engage a trailing weft-end as the clearer returns forward to its normal position.

10. Trailing weft-end clearer devices comprising a stationary support, a weft-clearer movably mounted on said support, occupying a retracted forward position while the lay is rearward, and actuated by the advancing lay to move its engaging portion into a rearward position adapting such portion to

engage a trailing weft-end as the clearer returns forward to its normal position, said weft-clearer adapted to clamp the thus-engaged trailing weft-end.

- 5 11. Trailing weft-end clearer devices comprising a stationary support, a weft-clearer arm mounted pivotally in connection with said support, occupying a retracted forward position while the lay is rearward, and actuated by the advancing lay to move its engaging portion into a rearward position adapting such portion to engage a trailing weft-end as the clearer returns to its normal position.
- 10

12. Trailing weft-end clearer devices comprising a stationary support, a weft-clearer arm mounted pivotally in connection with said support, occupying a retracted forward position while the lay is rearward, and actuated by the advancing lay to move its engaging portion into a rearward position adapting such portion to engage a trailing weft-end as the clearer returns to its normal position, said weft-clearer arm adapted to clamp the thus-engaged trailing weft-end.

JAMES ALLEN SWAINBANK.
